UNITED STATES PATENT OFFICE.

GORDON A. STEIN, OF WINDSOR, ONTARIO, CANADA.

COMBINED IRONING BOARD AND TABLE.

1,402,024.

Specification of Letters Patent.

Patented Jan. 3, 1922.

Application filed September 5, 1919. Serial No. 321,857.

To all whom it may concern:

Be it known that I, GORDON A. STEIN, a citizen of the British Empire, residing at Windsor, in the Province of Ontario and 5 Dominion of Canada, have invented certain new and useful Improvements in a Combined Ironing Board and Table, of which the following is a specification.

The invention relates to a combined ironing board and table.

The primary object of the invention is the provision of a combined ironing board and table, wherein the ironing board is movably mounted in the frame of the table 15 so that either may be used separately in the ordinary well known manner, or together, the ironing board when not in use being concealed from view in the table frame and out of the way, so as not to interfere with the free use of the table, and when 20 it is desired to use the ironing board the same can be conveniently pulled outwardly into position at one end of the table.

Another object of the invention is the provision of a combined ironing board and table 25 wherein the ironing board is supported in a novel manner within the table, so that said board can be readily and conveniently moved inwardly within the frame of the table or 30 pulled outwardly, the board when pulled outwardly being adapted for use for ironing purposes, without any possibility of the sagging thereof and when within the table frame will also be held against sagging.

35 A further object of the invention is the provision of a combined ironing board and table of this character, wherein the mounting of the board in the table does not detract from the appearance of the latter and is in 40 convenient position, so that the said board can be pulled outwardly and supported for use, thereby eliminating the necessity of storing the board in a cupboard or placing the same within a corner of a room, as is 45 usual, the board being handy to the user of the table and when it is not in use is stored beneath the table top to occupy the least possible space and would be out of view, while the table may be used in the ordinary well 50 known manner.

A still further object of the invention is the provision of a combined ironing board and table of this character, which is comparatively simple of construction, thor-

oughly reliable and efficient in its purpose, 55 strong, durable and inexpensive to manufacture.

With these and other objects in view the invention consists of the features of construction, combination and arrangement of 60 parts, as will be hereinafter fully described, illustrated in the accompanying drawings and pointed out in the claim hereunto appended.

In the accompanying drawings: 65

Figure 1 is a vertical longitudinal sectional view through the table showing a fragmentary portion of the ironing board extending therefrom.

Figure 2 is a bottom plan view of the table 70 showing the ironing board disposed within the frame of the table when not in use.

Figure 3 is a fragmentary side elevation of a portion of the ironing board showing the supporting legs and adjunct parts when 75 in position for use.

Similar reference characters indicate corresponding parts throughout the several views in the drawings.

Referring to the drawings in detail, A designates generally a table of the ordinary wellknown construction, and B an ironing board, the latter being combined with the table, which comprises the usual top frame 10, table top 11 and supporting legs 12 which 85 are fixed in any suitable manner to the frame 10 at the corners thereof.

The ironing board B comprises the usual board section 13, which is tapered toward one end and is preferably of ordinary well 90 known shape.

Arranged within the table frame 10 of the table A, spaced from the sides thereof are longitudinally disposed parallel guide rods 14 serving as tracks which at the ends 15 thereof are passed through the end piece of the frame 10 of the table and have threaded thereon lock nuts 16 for the fastening of the said ends in the frame, while the opposite laterally out-turning ends 17 of the said 100 rods 14 are passed transversely through the legs 12 adjacent thereto and the sides of the frame 10 near the other end piece of the latter and have threaded thereon nuts 18 for securing said ends 17 thereto.

The frame 10 at the end adjacent to the laterally outturned ends 17 of the rods 14 is formed with a suitable cutaway portion or

doorway 19 adapted to be closed by a swinging door 20 which is hinged or otherwise fastened to the table frame and is adapted to be moved to closed position in the doorway 19 or brought to an open position, the door 20 being provided with a suitable latch 21 to fasten it closed.

Adapted to work through the cutaway portion or doorway 19 is the board 13 which 10 at its inner end is supported for sliding movement between the rods 14, the said board being fitted with suitable eye members or guides 22, which loosely embrace the rods 14 so that said board can be pulled outwardly to the position shown in Figure 1 of the drawings or pushed inwardly beneath the table top 11 within the frame 10 as shown in Figure 2 of the drawings.

Hinged or otherwise swingingly connected to the board 13 near its outermost end is 20 a supporting leg 23, the hinge 24 connecting it to said board and permits the folding and unfolding of said legs. Secured to the underface of the board 13 spaced from 25 the hinge 24 is a bearing 25 to which is pivotally connected one end of the swinging brace 26 having a longitudinal slot 27, formed with a lateral branch or notch 29 to receive a keeper 28 when the leg 23 has been 30 unfolded or brought to supporting position relative to the board 13, so that the said brace 26 will be locked in bracing position, as is clearly shown in Figure 4 of the drawings to prevent accidental folding of the leg 35 23. The outer free end portion 30 of the brace 26 is angularly bent to provide a handle thereto for permitting manual manipulation of the said brace to permit the locking of the same with the keeper or the unlocking of 40 the brace from said keeper for the fastening of the leg in supporting position or to permit the unfolding thereof.

Secured to the frame 10 of the table below the doorway 19 is a bracket 31 which 45 serves to support the board 13 when pushed inwardly within the frame 10 to prevent the sagging of said board when not in use. It will be apparent that when the board 13 is within the frame 10 of the table it is concealed from view, this being the normal position of the board when not in use, so as to be out of the way and not interfere with access to the table. Thus it will be apparent that when the ironing board is not in use it

occupies what might otherwise be wasted 55 space in the table frame.

Carried upon the leg 23 of the board 13 is a swinging latch 32, which is adapted to engage the brace 26 when the leg is folded to prevent the unfolding of the leg after 60 the board 13 has been pushed inwardly of the table frame, the latch 32 being shifted out of the path of the brace to permit the unfolding of the leg 23 and the locking of the brace therewith.

It is to be understood that the doorway 19 in the end of the table frame 10 is of a size to permit the passage of the board 13 and the leg 23 when folded for the sliding of the ironing board inwardly upon said 70 frame 10 or outwardly to the position shown in Figures 1 and 2 of the drawings.

The doorway 19 is normally closed by the door 20 when the board 13 and its foldable leg are confined within the table frame 10 so 75 that said ironing board is entirely concealed and hidden from view.

From the foregoing it is thought that the construction and manner of use of the combined ironing board and table will be clearly 80 understood and, therefore, a more extended explanation has been omitted.

What is claimed is:

The combination with a table having a top provided with a frame intermediately beneath the same formed with an opening at one end of said table, substantially L-shaped, longitudinally disposed, parallel guides extending throughout the length and beneath the table top, means for fastening the terminals of said guides to one end of the frame, the opposite threaded terminals of said guides extending transversely through the legs and sides of the said frame, nuts on the threaded terminals of said guides 95 for securing said terminals to the sides of said frame, an ironing board movable through the opening in the end of the frame and having eyes slidably engaged with the guides, means for supporting the outer end 100 of the board when it is moved inwardly relatively to the table, and means for supporting the said outer end when the board is moved outwardly relatively to said table.

In testimony whereof I affix my signature 105 hereto.

GORDON A. STEIN.
